UNITED STATES PATENT OFFICE.

GEORGE L. GRIGSBY, OF WAITSBURG, WASHINGTON.

TRACE-LOOP.

1,218,080.

Specification of Letters Patent. Patented Mar. 6, 1917.

Application filed May 13, 1916. Serial No. 97,360.

To all whom it may concern:

Be it known that I, GEORGE L. GRIGSBY, a citizen of the United States, residing at Waitsburg, in the county of Walla Walla and State of Washington, have invented certain new and useful Improvements in Trace-Loops, of which the following is a specification.

This invention relates to trace loops and more particularly to an improvement in the loops which are employed to fasten the hip straps to the breeching and shoulder straps of a harness to the trace.

The primary object of the invention is the provision of a loop adapted to be fastened to the trace or to the breeching which will be provided with means for preventing the end of the hip strap or shoulder strap from wearing or injuring the leather of which the breeching or trace is constructed.

A further object of this invention is the provision of a loop which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which,

Figure 1 is a side elevation of a fragment of a trace showing the invention applied thereto.

Fig. 2 is a vertical section on the line 2--2 of Fig. 1.

Fig. 3 is a vertical section on the line 3--3 of Fig. 1.

It is well known, in the art of harness making, that the loops at the ends of the saddle strap, and belly-band which are attached to the traces, constantly strike against the edge of the traces thereby causing the leather to become worn so that the traces are weakened, making repairs necessary. It is my intention to obviate this defect by protecting the edge of the trace from contacting with the ends of the loops on the saddle strap, belly-band and shoulder strap.

The forward end of the trace is provided with a double loop, designated in its entirety by the numeral 1 and the main or body portion of the loop consists of a central plate 2 which has extending outwardly from its opposite ends the arms 3 connected to-

gether at their terminals by the rod 4. Loosely mounted upon the rod 4 is a sleeve 5 which is free to rotate upon the rod. A plurality of apertures 6 are formed in the plate 2 and have rivets 7 extended through the same for fastening the plate to the trace A. The arms 3 are connected together by connecting brace arm 8 which is secured to the arms 3 at its ends in a position whereby it will be disposed at the upper edge of the trace A. As shown by Fig. 2 of the drawing, the brace arm 8 has integrally formed therewith the laterally extending flange 9 which extends across the upper edge of the trace A. The upwardly extending arms 3 are slightly rearwardly curved for disposing the sleeve 5 directly above the center of the flange 9 whereby the loop B formed in the end of the saddle strap will contact in its downward movement with the flange 9 and protect the edge of the trace A.

Depending from the lower edge of the plate 2 is a pair of arms 3' which are similar in construction to the arms 3 and supporting the rod 4' upon which the sleeve 5' is mounted. A brace arm 10 connects the arms 3' and is disposed at the lower edge of the trace A and has its lower edge extending slightly below the edge of the trace A. The sleeve 5' receives the loop C formed in the ends of the belly-band of the harness and the brace 10, by virtue of its extended edge, prevents the loop C from striking the lower edge of the trace A.

Mounted upon a portion of the trace A is the shoulder strap receiving loop, designated in its entirety by the numeral 11, which consists of the plate 12 fastened to the trace by the rivets 13. Extending upwardly from the plate 12 are the two arms 14 having their terminals joined together by the rod 15 which carries the sleeve 16 adapted to receive the loop D formed at the end of the shoulder strap. The upper edge of the plate 12 terminates at the edge of the trace A and has integrally formed therewith the laterally extending flange 17 which extends from the upper edge of the trace A for preventing the loop D from striking the edge of the trace.

In reduction to practice I have found that the form of my invention illustrated in the drawings and referred to in the above description, as the preferred embodiment, is the most efficient and practicable, yet realizing that the conditions concurrent with the

adopt. ⁵ of my device will necessarily vary, I desire to emphasize the fact that various minor changes in the details of construction, proportion and arrangement of parts may be resorted to, when required, without sacrificing any of the advantages of my invention, as defined in the appended claims.

I claim:

1. The combination with a harness trace, ¹⁰ of a loop mounted upon the trace, the said loop consisting of a plate relatively wide along the line of the longitudinal center of the said trace, a plurality of arms extending from each edge of the plate, the said arms ¹⁵ being so curved that their terminals are disposed directly over the center of the edge of the said trace, a laterally projecting flange having its terminals fixed to the said arms and extending from one edge of the plate, ²⁰ and a sleeve carried by each pair of said arms for receiving, respectively, the saddle strap and belly-band.
2. The combination with a harness trace, ²⁵ of a loop mounted upon the trace, the said loop consisting of a plate relatively wide along the line of the longitudinal center of the said trace, a plurality of arms extending from each edge of the plate, the said arms being so curved that their terminals are disposed ³⁰ directly over the center of the edge of the said trace, a sleeve carried by each pair of said arms for receiving, respectively, the saddle strap and belly-band, the terminals of

each of the said arms being slightly curved and extended toward each other for bringing the ends of each pair in relatively close relationship, and a brace arm connecting the ends of each pair of arms where they join the said plate. ³⁵

3. The combination with a harness trace, ⁴⁰ of a loop mounted upon the trace, the said loop consisting of a plate relatively wide along the line of the longitudinal center of the said trace, a plurality of arms extending from each edge of the plate, the said arms ⁴⁵ being so curved that their terminals are disposed directly over the center of the edge of the said trace, a sleeve carried by each pair of said arms for receiving, respectively, the saddle strap and belly-band, the terminals of each of the said arms being slightly curved and extended toward each other for bringing the ends of each pair in relatively close relationship, and a brace arm connecting the ends of each pair of arms where they join the said plate, one of the said brace arms carrying a laterally extending flange arranged to extend across the edge of the said trace. ⁵⁰

In testimony whereof I affix my signature in presence of two witnesses.

GEORGE L. GRIGSBY.
